W. H. Morrison

UNITED STATES PATENT OFFICE.

GEORGE R. LOGAN, OF BROOKLYN, NEW YORK.

CUFF-PROTECTOR.

1,263,446.

Specification of Letters Patent. Patented Apr. 23, 1918.

Application filed May 23, 1914. Serial No. 840,548.

To all whom it may concern:

Be it known that I, GEORGE R. LOGAN, a citizen of the United States, residing in the borough of Brooklyn, in the county of Kings 5 and State of New York, have invented certain new and useful Improvements in Cuff-Protectors, fully described and represented in the following specification and the accompanying drawings, forming a part thereof.

10 My invention relates to wearing apparel and pertains more particularly to shirt cuff devices, having for an object to provide an unobtrusive yet serviceable over-cuff.

To this end my cuff in its general aspect 15 meets the requirements of an ordinary cuff, to which are added means for covering the wearing portions of the cuff over which it may be worn to protect the latter from injury and soiling; and also my over-cuff may 20 be used to conceal defective or damaged portions of the cuff proper by means of a fabric counterpart similar in appearance to the texture of the cuff itself, which may when desired be made of the same material and 25 pattern as the shirt cuff itself, and not distinguishable therefrom.

Heretofore articles of this class have been devised as cuff protectors, so called, which are frequently made of impervious materials, 30 usually in stiff, unwieldy forms, and also of paper of various designs intended to be used once and thrown away, with no attempt to have such protecting cuff appear otherwise than a superimposed device.

35 This disadvantage in itself, it can readily be understood, would often tend to detract from if not wholly destroy the benefits of an effective protective device of the class described.

40 Hence, it is one of the purposes of my invention to provide a supplemental cuff made of linen or other desirable fabric of a similar flexible nature which in its general outline and appearance may be made to conform 45 to the shape of the usual wristband or cuff of a shirt, having portions that may be folded or turned back under the cuff proper, to cover both the edges at the end and at the sides of the cuff, and also to cover those 50 portions of the surface thereof which are the most readily soiled in wearing.

Referring to the drawings: Figure 1 is 55 a view of a preferred form of my cuff protector shown flat or opened; Figs. 2 and 3 are similar partial views of modified forms of my over-cuff; Fig. 4 shows my protector

applied to an ordinary shirt cuff, preparatory to folding-in the end flaps; Fig. 5 is a view similar to Fig. 4 with flaps turned under; and Fig. 6 shows a sectional view of the 60 cuff and protector.

Referring to the drawings, 1 represents a preferred form of my over-cuff having what may be termed the body portion 2 with button-holes 3 worked near the ends in the usual 65 manner of cuff-designing. In addition to the holes 3 other holes 3^a may be set in alignment therewith circumferentially of the over-cuff to admit of its being buttoned on over cuffs of different sizes when necessary, 70 and for other reasons presently to be explained.

The holes 3 and 3^a conform in general construction to the usual form of button-hole as shown, but one at least thereof would 75 preferably have an enlarged opening 4 through which the head of the cuff button may easily pass, with the narrowed part 4^a extending therefrom to receive the shank 80 of the button.

Either one or both sides of my over-cuff may be extended to form a flap 5, and a similar extension 6 may be added at one or both ends of the cuff, for the purpose of being turned around and under the corresponding edges of the cuff so as to conceal and protect those portions, as illustrated in Fig. 5. The flap 6 is divided substantially midway of its length into component portions 7 and 8 respectively. The flap 7 will 90 therefore protect the upper inner side of a cuff when worn in the usual manner and likewise the portion 8 will protect the under portion of the interior part of the cuff.

The flap 6 if made in a single member, 95 would form objectionable wrinkles or creases that would not only produce discomfort for the wearer but would interfere with the proper and convenient adjustment of the device upon and around the cuff. The bifurcation 6 can be any sort of an incision, 100 preferably at right angles to the edge of the cuff, extending substantially to the portion to which the edge of the cuff proper normally extends.

The flap 5 need be given only sufficient 105 length to insure its being held securely in its position surrounding the edge at the sides of the cuff, and, if desired to have it reach beyond the point where the cuff 110 button extends through the cuff, a notched opening or buttonhole 9 may be formed in

the outer edge thereof to clear the shank or links of the button, as shown in Fig. 3. Or, as shown in Fig. 2, by suitably placing a button-hole 3 within the flap 5 at the point 5 through which the stem of the button may pass before being inserted into the under cuff, secured by such button-hole, the over-cuff may then be drawn around the edge of the under cuff in the same manner as the 10 flaps 7 and 8 are shown folded back as in Figs. 5 and 6, and again inserted over the button to hold the flap more securely in position.

In actual use, however, it has been found 15 that when the cuff is made of a fabric of reasonable body strength, the notch above described is sufficient for all practical purposes, although the hole in the flap 5 when placed with care at the proper distance from 20 the adjacent hole in the body portion, acts to draw the parts into more accurate adjustment, and hold the cuff in such adjusted position until detached.

The insertion of the second hole 3^a thus 25 creates the lateral flap 5 to the cuff, which flap may be carried over one edge only of the cuff, in the manner indicated in Fig. 6, or folded upon the broken line indicated at *a* in Fig. 2 or Fig. 3, and carried around 30 both the contiguous edges of the cuff, if desired. In the former practice, however, as pointed out, the usual appearance of a cuff is more perfectly simulated.

A portion of each of the flaps 7 and 8 35 is cut away at the end as shown at each corner of the cuff as at 10, so that the shank of the cuff button will not interfere with the folding under of the flaps 7 and 8, in the manner described, when those flaps are de- 40 sired to be given a greater length than sufficient to carry them back to the cuff buttons. In using certain lightweight material or using fabric of a loose form, I have found it preferable to give added length to the flap 45 portion of the over-cuff.

The bifurcated flap 6 of the form illus- 50 trated may if desired be attached to both edges of the cuff, as illustrated in the drawings, whereby four possible changes of the cuff are made available; that is to say, the

over-cuff may be worn either side out and changed end for end.

Having described my invention, what I claim is:

1. As an article of manufacture, an over-cuff of flexible material, having button-holes for attaching to the buttons of an underlying shirt cuff, and a medially divided edge or flap adapted to be folded over said under cuff, the bifurcation thereof extending substantially to the corresponding edge of said cuff, substantially in the manner described. 55

2. As an article of manufacture, an over-cuff of flexible material, having button-holes for attaching to the buttons of an underlying shirt cuff, a medially divided edge or flap adapted to be folded over said under cuff, the bifurcation thereof extending substantially to the corresponding edge of said 60 cuff, and a lateral flap similarly adapted to be folded over the side of said under cuff, substantially in the manner described. 65

3. As an article of manufacture, an over-cuff of flexible material with a medially divided edge or flap adapted to be folded over an underlying shirt cuff and having the bifurcation thereof extending substantially to the position of the corresponding edge of the said under cuff, a lateral flap thereon 70 adapted to be folded over the corresponding edge of said under cuff, and a plurality of button holes arranged in longitudinal alinement thereon and adapted to attach the same to the buttons of said cuff, one of said holes being located in said lateral flap. 75

4. As an article of manufacture, an over-cuff of flexible material with a medially divided edge or flap adapted to be folded over an underlying shirt cuff, and having the bifurcation thereof extending substantially to the position of the corresponding edge of said under cuff, button-holes for attaching to said cuff, and a lateral flap upon the side thereof having a notched portion in longitudinal alinement with the button-holes 80 thereon. 90

In testimony whereof, I have hereunto set my hand.

GEORGE R. LOGAN.
